Patented May 14, 1974

231,652

SCISSORS

Mikko Tapani Jantti, Itainen Puistotie 4 A 1,
00140 Helsinki 14, Finland

Filed Jan. 23, 1973, Ser. No. 326,018

Claims priority, application Sweden Aug. 16, 1972

Term of patent 14 years

Int. Cl. D8—03

U.S. Cl. D8—57

FIG. 1 is a side perspective view of scissors showing my new design;

FIG. 2 is a perspective view of the other side thereof in an open position;

FIG. 3 is an elevational view of the side shown in FIG. 1;

FIG. 4 is an edge view thereof;

FIG. 5 is a bottom end view; and

FIG. 6 is a top end view.

I claim:

The ornamental design for a scissors, substantially as shown.
